GAS COOKING STOVE OR RANGE

Filed Nov. 29, 1929

UNITED STATES PATENT OFFICE

ALFRED J. REEDY, OF BATTLE CREEK, MICHIGAN, ASSIGNEES TO A-B STOVE COMPANY,
OF BATTLE CREEK, MICHIGAN, A CORPORATION OF MICHIGAN

GAS COOKING STOVE OR RANGE

Application filed November 28, 1929. Serial No. 410,274.

The main object of this invention is to provide in a gas cooking stove or range an improved housing structure for the manifold and valve casings which while they are effectively concealed are readily accessible for removal of the valve or parts thereof.

A further object is to provide a structure having these advantages which is very attractive in appearance and at the same time economical in structure.

Objects relating to details and economies of my invention will appear from the description to follow. The invention is defined and pointed out in the claims.

15 A structure which is a preferred embodiment of my invention is illustrated in the accompanying drawing, in which:

Fig. 1 is a front elevation of a gas cooking stove embodying the features of my invention, the legs being partially broken away.

Fig. 2 is a fragmentary view partially in vertical section on line 2-2 of Fig. 1.

Fig. 3 is an enlarged fragmentary front elevation of the front wall.

25 Fig. 4 is a fragmentary sectional view of the parts shown in Fig. 2 in disassembled relation.

Referring to the drawing, the embodiment of my invention illustrated comprises an 30 open cooking top designated generally by the numeral 1, and an oven and broiler unit 2.

The cooking or burner chamber top 3 is as usual in gas stoves provided with a suitable grid not illustrated. I show only a single burner 4 but it will be understood that in practice a plurality of burners are provided. However, as the arrangement of these burners in the burner chamber 5 below the cooking top constitutes no part of this invention, 40 they are not illustrated herein.

6 represents the drip pan which constitutes the bottom of the burner chamber.

The front wall 7 of the open cooking top unit is formed as a casting and is provided 45 with a horizontal outwardly offset housing 8 at its upper edge, this housing extending approximately the full length of the front wall and constituting a front wall for the burner chamber.

60 The top wall 9 of the housing is upwardly

inclined and provided with a shoulder-like joint seat 10 for the lower edge of the flange 11 on the top 3, this flange overlapping the edge of the housing so that a substantially inconspicuous joint is provided at this point. 55

The face wall 12 of the housing has valve handle shank openings 13 therein, the structure illustrated having six valves, the handles 14 being the only parts exposed or on the outside of the housing. The housing face 60 also has grids 15. The housing is formed integrally with the front wall 7.

The manifold 16 is arranged on the inner side of the front wall 1 which is provided with internal boss-like projections 17 having 65 curved seats 18 for the manifold.

The clamps 19 engage the inner sides of the manifold, these clamps being detachably secured to the supports by means of screws 20. The manifold is thus supported in a 70 plane above the plane of the housing.

The valve casings 21 are provided with threaded nipples 22 by means of which the valve casings are detachably secured to the manifolds, the manifolds having tapped 75 openings 23 on their under sides into which the nipples are threaded. The valve casings are provided with nozzles 24 delivering to the burner.

The valve 25 which is of the rotary plug type is provided with a threaded stem 26 80 projecting into the housing.

The handle 14 is provided with a shank 27 threaded upon the stem and secured thereto by means of the set screws 28. This set screw 85 is accessible through an opening 29 in the bottom wall of the housing.

With the parts thus arranged, the valves may be removed by first removing the handle, shifting the burner to release the nozzle, 90 and the valve may then be rotated to unscrew its nipple, the housing affording sufficient space for the swing of the valve stem and nipple.

I have illustrated only a single valve and 95 burner but it will be understood that the others are merely duplicates.

Gas stoves or ranges embodying my improvements are very attractive in appearance, at the same time economical in the 100

matter of its parts and the parts being easily assembled and disassembled.

I have not attempted to illustrate other adaptations or embodiments of my improvements as it is believed that this disclosure will enable those skilled in the art to embody or adapt the same as may be desired.

Having thus described my invention, what I claim as new and desire to secure by Letters Patent, is:

1. A gas stove comprising a burner chamber top having a depending flange at its front edge, a front wall having a horizontal outwardly offset housing at its upper edge integral therewith, the top wall of said housing being outwardly inclined and having an upwardly facing joint shoulder at its inner edge coacting with the edge of the flange on said top frame, the face of said housing having a valve handle shank opening and an air inlet grid, said front wall being also provided with an inwardly projecting boss-like manifold support, a manifold disposed horizontally on said support, a clamp detachably mounted on said support for securing said manifold thereto, the manifold being disposed in a plane above said housing, a burner disposed below said burner chamber top, a valve casing having an upwardly projecting inlet nipple threaded into the under side of said manifold and a nozzle delivering to said burner, a valve provided with a stem projecting into said housing, and a valve handle arranged on the outside of said housing and having a shank disposed through said handle shank opening and detachably connected to said stem.

2. A gas stove comprising a burner chamber top, a front wall having a horizontal outwardly offset housing at its upper edge integral therewith, the face of said housing

45 having a valve handle shank opening and an air inlet grid, a manifold, a burner disposed below said burner chamber top, a valve casing having an upwardly projecting inlet nipple threaded into the under side of said manifold and a nozzle delivering to said burner, a valve provided with a threaded stem projecting into said housing, and a valve handle arranged on the outside of said housing and having a shank disposed through said handle shank opening and threaded upon said stem, said handle shank being provided with a set screw, the bottom wall of said housing having an opening therein through which access may be had to said set screw.

60 3. A gas stove comprising a burner chamber top having a depending flange at its front edge, a front wall having a horizontal outwardly offset housing at its upper edge integral therewith, the top wall of said housing being outwardly inclined and having an up-

wardly facing joint shoulder at its inner edge coacting with the edge of the flange on said top frame, the face of said housing having a valve handle shank opening and an air inlet grid, said front wall being also provided with an inwardly projecting boss-like manifold support, a manifold disposed horizontally on said support, a clamp detachably mounted on said support for securing said manifold thereto, the manifold being disposed in a plane above said housing, a burner disposed below said burner chamber top, a valve casing having an upwardly projecting inlet nipple threaded into the under side of said manifold and a nozzle delivering to said burner, a valve provided with a stem projecting into said housing, and a valve handle arranged on the outside of said housing and having a shank disposed through said handle shank opening and detachably connected to said stem.

4. A gas stove comprising a burner chamber top, a front wall having a horizontal outwardly offset housing at its upper edge integral therewith, the face of said housing having a valve handle shank opening and an air inlet grid, a manifold disposed at the rear of said front wall, a burner disposed below said burner chamber top, a valve casing having an upwardly projecting inlet nipple threaded into the under side of said manifold and a nozzle delivering to said burner, a valve provided with a stem projecting into said housing, and a valve handle arranged on the outside of said housing and having a shank disposed through said handle shank opening and detachably connected to said stem.

5. A gas stove comprising a cooking top, a front wall having a horizontal outwardly offset housing at its upper edge integral therewith, the face of said housing having a handle shank opening and an air inlet grid, said front wall being also provided with an inwardly projecting manifold support, a manifold disposed horizontally on said support, a burner disposed below said cooking top, a valve casing detachably mounted on the under side of said manifold and having a nozzle delivering to said burner, a valve provided with a threaded stem projecting into said housing, and a valve handle arranged on the outside of said housing and having a shank disposed through said handle shank opening and threaded upon said stem.

6. A gas stove comprising a cooking top, a front wall having a horizontal outwardly offset housing at its upper edge integral therewith, the face of said housing having a handle shank opening and an air inlet grid, a manifold disposed on the inner side of said wall, a burner disposed below said cooking top, a valve casing detachably mounted on said manifold and having a nozzle delivering to said burner, a valve provided with a stem

projecting into said housing, and a valve handle arranged on the outside of said housing and having a shank disposed through said handle shank opening and detachably connected to said stem.

7. A gas stove provided with a burner chamber and a front wall having a horizontally disposed outwardly offset housing constituting a front for said burner chamber, the face of said housing having a valve handle shank opening and an air inlet grid, a manifold mounted on the inner side of said front wall in a plane above said housing, a burner disposed within the burner chamber, a valve casing having an upwardly projecting nipple threaded into the inner side of said manifold and provided with a nozzle delivering to said burner, a valve provided with a threaded stem projecting into said housing, and a handle arranged on the outside of said housing and having a shank disposed through said handle shank opening and threaded into said stem, said handle shank being provided with a set screw, the bottom wall of said housing having an opening therein through which access may be had to said set screw.

8. A gas stove provided with a burner and a front wall having a horizontally disposed outwardly offset housing constituting a front for said burner chamber, the face of said housing having a valve handle shank opening and an air inlet grid, a manifold mounted on the inner side of said front wall in a plane above said housing, a burner disposed within the burner chamber, a valve casing detachably mounted on the under side of said manifold and having a nozzle delivering to said burner, a valve provided with a stem projecting into said housing, and a handle provided with a shank disposed through said handle shank opening in said housing face and detachably connected to said stem.

9. A gas stove provided with a burner and a front wall having a horizontally disposed outwardly offset housing constituting a front for said burner chamber, the face of said housing having a valve handle shank opening and an air inlet grid, a manifold mounted on the inner side of said front wall, a burner disposed within the burner chamber, a valve casing detachably mounted on said manifold and having a nozzle delivering to said burner, a valve provided with a stem projecting into said housing, and a handle provided with a shank disposed through said handle shank opening in said housing face and detachably connected to said stem.

In witness whereof I have hereunto set my
60 hand.

ALFRED J. REEDY.
